UNITED STATES PATENT OFFICE.

ARTHUR B. SPERRY, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed November 6, 1924. Serial No. 748,050.

To all whom it may concern:

Be it known that I, ARTHUR B. SPERRY, a citizen of the United States, residing at New York city, in the county of New York and State of New York, have invented certain new and useful Improvements in Telephone-Exchange Systems, of which the following is a full, clear, concise, and exact description.

10 This invention relates to telephone exchange systems and more especially it has to do with telephone systems of the class wherein automatic switching apparatus is employed in a main exchange for the establishment of conversational connections between two other main exchanges.

For the sake of clearness the two latter exchanges will be referred to hereinafter as the originating and terminating offices, respectively, while the intermediate exchange will be known as the tandem office. In this disclosure of the invention the apparatus employed in the originating office is of the semi-automatic switching type and that used in the terminating office is of the manually operated type. In this system the means in the tandem office for establishing a connection comprise step-by-step selector or trunk-hunting switches.

30 The object of the invention is an improved method for preventing trunk-hunting over a selector switch bank should all the trunks in the desired group be busy and for permitting the hunting when a trunk in that group becomes idle.

A feature of the invention resides in the manner in which the operator is kept informed of the progress of the connection.

Other features and advantages will be apparent after a consideration of the following detailed description and the appended claims.

45 The drawings consisting of two figures illustrate a complete trunk connection between two offices, the connecting means being located in an intermediate or tandem office. Fig. 1 shows a calling substation, an operator's dialing cord circuit, and a trunk outgoing from the originating office, and Fig. 2 shows trunks incoming and outgoing from the tandem office together with the associated automatic switching apparatus and also the extension of the trunk to the terminating office.

55 The calling substation 100 is adapted upon

the removal of the receiver thereat to cause the lighting of a line lamp before the operator in the usual manner. In response to the lighting of the lamp, not shown, the operator inserts the answering end of one of 60 the position cord sets into the jack associated with the lighted lamp and depresses the listening key 104 associated with the selected cord circuit to connect her head set to the calling substation. After receiving the 65 number of the desired party, assuming that the called party's line is located in a distant office and is available only through a tandem office, the operator with the calling end of the selected cord circuit tests in the usual 70 way for busy trunks leading to the tandem point and then plugs into the jack that is connected to the first idle trunk. When the calling plug is fully inserted in the trunk jack a circuit is closed from ground, 75 through the windings of sleeve relay 107 and relay 106, lamp 105 to battery. Relays 106 and 107 operate, relay 107 closing an obvious circuit to operate relay 108. The operation of relay 108 closes at its inner 80 right armature an operating circuit for relay 109 the circuit being traceable from battery, through the lower right winding of repeating coil 118, through the winding of relay 103, ring side of the cord and trunk 85 circuits, conductor 121, normal contact of relay 109 and through winding thereof to ground at the inner right armature of relay 108. Relay 109 operates and locks at its inner left contact in a circuit extending to 90 battery at the outer left armature of relay 108. The relay 109 connects at its outer left armature, the winding of relay 110 to the ring side of the trunk circuit, and closes at its inner right armature an obvious operating 95 circuit for the pulsing relay 113. The operation of relay 113 connects the bridge of the polarized relay 114 across the conducting end of the trunk circuit, thereby preparing the selected trunk circuit to the 100 tandem office for dialing.

The operator now depresses her dialing key 115 and operates the position dial 116 to connect the selected idle trunk to another 105 idle trunk outgoing from the tandem office to the particular office in which the called subscriber's line terminates. When the dial moves off normal position, the circuit previously prepared at the outer left armature of relay 109 is closed at the left spring and 110

inner contact of the dial to operate the relay 110, the circuit being traceable from battery at outer left armature of relay 108, through the winding of relay 110, contact 5 and armature of relay 117, outer left armature and contact of relay 109, conductor 121, ring side of trunk and cord circuits, lower off-normal contacts of key 115 to ground at inner left contact of the dial. During the 10 time that the dial is in off-normal position, this ground connection remains steady to hold the relay 110 operated during the sending of the pulses. The operation of relay 110 opens at its make-before-break contact 15 the operating circuit for pulsing relay 113 but closes simultaneously at its inner right armature and front contact another operating circuit extending to ground at the right-hand spring of the dial 116. This 20 substitute ground holds the relay 113 operated until the operator releases and permits the dial to return to normal, which return movement causes interruptions in this substitute ground connection corresponding in 25 number to the digit dialed.

For each pulse received by relay 113, a circuit is closed extending from battery, through the right-hand winding of relay 203, outer normal contact of relay 204, outer 30 left armature and back contact of relay 208, ring side of trunk, through the winding of polarized relay 114, contact and armature of relay 113, tip side of trunk, inner left armature and back contact of relay 208, inner 35 normal contact of relay 204, through the left-hand winding of relay 203 to ground. A direct bridge across the tip and ring of the trunk is also closed through the inner left front contact of relay 110. Pulsing relay 40 203 operates in this circuit but relay 114 due to its polarity is not affected. The first pulse operating relay 203 causes the operation of relay 205 which, being of the slow-to-release type, is maintained in an 45 operated condition during the subsequent pulses of the digit dialed. At the end of the first pulse relay 203 deenergizes and closes at its back contact an operating circuit for the primary stepping magnet 206 50 of the selector switch which is associated with the particular trunk selected, the circuit being traceable from battery, through the winding of magnet 206, left-hand low resistance winding of relay 207, left front 55 contact of relay 205, back contact of relay 203 to ground at the inner right armature of relay 208. Relay 207 is made slow-to-release so as to be non-responsive to the 60 subsequent pulses of the dialed digit. The relay 207 and the magnet 206 operate, and the operation of the magnet starts the primary movement of the selector switch brushes 209, 216, 217 and 218 upwardly over their respective terminal banks, the brush 209 being associated with the commutator bank, each

level of which corresponds to a group of outgoing trunks leading to a terminating office. For each succeeding pulse the brush 209 is stepped upwardly one level until the desired group is reached. 70

When the brushes start their primary movement the lower contacts of off-normal springs 214 close an operating circuit for relay 215, the circuit being traceable from battery, through the winding of relay 215, 75 lower contacts of off-normal springs 214, right armature and front contact of relay 207 to ground at the right armature of relay 205. Relay 215 operates and prepares for its right armature an operating circuit 80 for the secondary stepping magnet 213, but due to the operated condition of relay 207, magnet 213 is prevented from operating.

Assuming that No. 1 on the dial corresponds to the group of trunks extending to the office in which the called subscriber's line terminates, one pulse will be transmitted by the dial and the brush 209 will step up to the first level and stop on terminal 210 which corresponds to the group of trunks extending to the desired office. After the pulse has been received by relay 203 and the relay has energized and subsequently deenergized, transmitting thereby a pulse to operate the magnet 206, the slow-to-release relay 207 de-energizes but only after a time sufficient to allow the off-normal contact springs 214 to close their contacts. The closing of these contact springs establishes a holding circuit for relay 215, the circuit being traceable 95 from battery, through the winding of relay 215, lower contacts of off-normal springs 214, armature and contact of magnet 213, left armature and contact of relay 215 to ground at inner right armature of relay 208. 100

If all the trunks in the desired group are busy, each of the respectively associated relays a , a^1 and a^2 of the chain relay group will be in an operated condition and the terminal 210 will be connected to ground at 110 the right armature of relay a^2 . With the brush 209 in contact with terminal 210 this ground connection completes a circuit extending through the right-hand high resistance winding of relay 207, to battery. This circuit holds the relay 207 in an operated condition so as to prevent the energization 115 of secondary stepping magnet 213, thereby holding the switch at a standstill until an idle trunk in the desired group is available. 120

In the meantime, the dial has returned to normal and the ground connection at the inner contact of the left-hand spring of the dial has opened, thereby deenergizing relay 110. Relay 110 opened at its inner right armature and front contact the pulsing circuit for relay 113, but the latter relay is immediately reenergized by the closing of the make-before-break contact of relay 110. The reenergization of relay 113 closes a 130

steady operating circuit for relay 203, the circuit being hereinbefore traced. Relay 203 is now held steadily energized but the relay 114 as in the previous case does not operate with the current flowing in the direction in the circuit described. The operation of relay 203 closes an operating circuit for relay 204, the circuit being traceable from interrupting battery, through the 10 winding of relay 204, left front contact of relay 207, front contact of relay 203 to ground at the inner right armature of relay 208. Relay 204 is made slow-acting in order to prevent its operation when relay 203 was 15 previously operated by the pulsing current. The operation of relay 203 also closes a parallel circuit to operate the relay 205, the operation of which closes a holding circuit for relay 215. The interrupter 232 effects 20 pulsations in the operating circuit for relay 204 in comparatively rapid succession, although considerably slower than the pulses which are transmitted by the dial, and these pulsations cause corresponding reversals of 25 battery and ground in the circuit through the winding of polarized relay 114. Relay 114 now responds to the repeated energizations of relay 204 and accordingly closes at its armature an intermittent operating circuit for supervisory relay 120, the circuit being traceable from battery, through the winding of relay 120, normal contact of the left-hand spring of dial 116, lower off-normal contact of key 115, ring side of cord 30 and trunk circuits, conductor 121, front contact of relay 114, outer right back contact of relay 110, through the winding of relay 117, tip side of trunk and cord circuits, inner contact of relay 106, upper off-normal 35 contact of key 115 to ground at the right spring of dial 116. Relays 117 and 120 energize and deenergize intermittently to correspond with the similar interruptions effective in relay 114, and the lamp 119 responds to these interruptions by flashing 40 thereby indicating to the operator that all trunks in the desired group are busy.

When an idle trunk in the desired group becomes available, its associated relay of the relay chain group a , a^1 and a^2 , is deenergized and opens the holding circuit for relay 207. The deenergization of relay 207 closes at its make-before-break contact the operating circuit for secondary stepping magnet 213, which circuit is traceable from battery, through the winding of magnet 213, right front contact of relay 215, make-before-break contact of relay 207 to ground at the right armature of relay 205. When the right front contact of relay 207 is opened, relay 215 is maintained operated in a circuit traceable from battery, through the winding of relay 215, lower contacts of off-normal springs 214, armature of magnet 213, left armature and contact of relay 215 to ground 50 at the inner right armature of relay 208. When magnet 213 operates, it opens at its armature and contact the holding circuit for relay 215 and the relay deenergizes, thereby opening the operating circuit for magnet 213. The deenergization of magnet 213 causes the brushes 209, 216, 217 and 218 to rotate over the terminals of the level in which the available trunk is located. The busy condition of the terminals with which 55 brush 216 is associated will close an operating circuit for relay 215 traceable from battery, through the winding of relay 215, lower contacts of springs 214, contact of magnet 213, outer right back contact of relay 208, conductor 230, brush 216 and its associated terminal to ground at the left armature of the busy trunk relay of the chain relay group. The energization of relay 215 again closes the operating circuit for 60 magnet 213, causing the brushes to rotate another step. This operation will be repeated until the available trunk is reached and relay 215 will not operate inasmuch as the trunk relay, such as a^2 , is in an unoperated condition, thereby preventing further operation of the stepping magnet 213. The seizure of the idle trunk removes the shunt around relay 208 and this relay having a 65 high resistance winding will operate in a circuit traceable from battery, through the winding of relay 215, lower contacts of springs 214, contact of magnet 213, through the winding of relay 208, contacts of spring 202, conductor 212 to ground at the right 70 armature of relay 205. Relay 215 does not operate in this circuit and the operation of relay 208 connects at its left armature the conductors of the incoming trunk with the conductors of the idle outgoing trunk. Also 75 the operation of relay 208 opens the operating circuit for relays 204 and 114. This causes the deenergization of supervisory relay 120 thereby opening the operating circuit for lamp 119. The lamp is extinguished 80 to indicate to the operator that an idle trunk in the desired group is seized.

Assuming that terminals 219, 220 and 221 are associated with the idle trunk, an operating circuit is closed for relay 222, the circuit being traceable from battery, through the right-hand winding of relay 222, right-hand normal contact of relay 225, lower left-hand winding of repeating coil 229, terminal 220, brush 217, ring side of trunk, outer left front contact of relay 208, ring side of trunk extending to the originating office, through the winding of relay 114, contact of relay 113 to tip side of trunk, inner left front contact of relay 208, tip side of trunk in tandem office, brush 218, terminal 221, upper left-hand winding of repeating coil 229, left-hand normal contact of relay 225, through the left-hand winding of relay 222 to ground. Relay 222 operates and closes at its 95

left armature, an operating circuit for trunk relay a^2 of the chain relay group. The operation of relay a^2 closes a holding circuit for relay 208, said circuit being traceable from ground at the left armature of relay a^2 , terminal 219, brush 216, conductor 230, outer right front contact of relay 208, contacts of spring 202, through the winding of relay 208, contact of magnet 213, lower contacts of springs 214, through the winding of relay 215 to battery. This holding circuit at the left armatures of relay 208 maintains the connection between the incoming and outgoing trunks in the tandem office. Also the operation of relay a^2 closes at its right armature a contact which builds up a closed circuit, when all the trunks of the group are busy.

The operation of relay 222 closes at its right armature an obvious operating circuit for high resistance relay 223. Relay 223 operates and causes lamp 226 to light indicating to the operator at the terminating office that a connection is desired with a subscriber's line terminating in her office, but relay 224 which is in the operating circuit for relay 223 does not operate at this time inasmuch as it is marginal. The operator in the terminating office inserts the answering end of one of her position cord circuits into the trunk jack associated with lamp 226 thereby causing the operation of relay 227. Relay 227 operates and opens the operating circuit for relay 223 and lamp 226, and therefore relay 223 deenergizes and the lamp 226 extinguishes, the supervision at the terminating office now being had at lamp 228. The insertion of the answering end of the selected cord circuit closes an obvious operating circuit for marginal relay 224 which now operates and closes at its contact an operating circuit for relay 225. Relay 225 operates and causes a reversal in the current flow through the polarized relay 114 and relay 114 consequently operates.

When the flashing of lamp 119 ceases, as hereinbefore described, indicating that an idle trunk is seized, the operator in the original office restores her dialing key 115 to normal and when relay 114 operates in the circuit in which the reversal of current is effected, the reversed current now being steady, closes an operating circuit for supervisory relay 103, the circuit being traceable from battery, through the lower right hand winding of repeating coil 118, through the winding of relay 103, ring side of cord and trunk circuits, conductor 121, front contact of relay 114, outer right back contact of relay 110, through the winding of relay 117, tip side of trunk and cord circuits, through the upper right hand winding of coil 118 to ground. Relay 103 operates and shunts lamp 105 which is extinguished and

remains thus for the duration of conversation.

Upon the cessation of the conversation the operator in the terminating office disconnects the cord circuit from the trunk and relay 227 deenergizes causing thereby the closing of the operating circuit for relay 223. Relay 223 reenergizes thereby causing the release of marginal relay 224 and the subsequent release of relay 225. The release of relay 225 changes the current flow from battery and ground at relay 222, through the winding of polarized relay 114 to its original direction and relay 114 deenergizes. The deenergization of relay 114 opens the operating circuit for supervisory relay 103 and relay 103 deenergizes thereby removing the shunt around lamp 105 which now lights indicating to the operator at the original office that the cord circuit at the terminating office has been disconnected. The originating operator will now disconnect her cord circuit from the calling subscriber's line and outgoing trunk circuit and the equipment in her office and the tandem office will restore to normal. The above operations are effective only, if it is assumed that the calling subscriber is still holding his line, but should the calling subscriber disconnect at the same time as the called subscriber, the remaining operated equipment, not restored in the above description, will restore to normal simultaneously with the equipment at the terminating office. The removal of the connections in the originating office opens the operating circuit for relay 107 which deenergizes and causes the subsequent release of relays 108, 109 and 113. The release of the armature of relay 113 opens the operating circuit for relay 222, thereby causing the subsequent release of relay a^2 and 223. The deenergization of relay a^2 opens the operating circuit for relay 208, thereby opening the connection between the incoming trunk and the associated selector switch brushes, and closing at the inner right back contact of relay 208 an operating circuit for the release magnet 231, the circuit being traceable from battery through the winding of relay 231, upper contact and spring 214, left back contact of relay 205, right back contact of relay 203 to ground at the right armature of relay 208. The operation of magnet 231 releases the switch brushes and permits them to return to normal. The release magnet 231 deenergizes when the off-normal springs 214 are restored with the switch brushes.

What is claimed is:

1. In a telephone system, a selector switch, a plurality of trunk lines arranged in groups extending from said switch, an operator's position, a sender at said position arranged to send impulses to select a trunk line in a particular group of said switch, a signal at

said position, means for preventing the selection of a trunk line and for flashing said signal should all trunk lines in the desired group be busy, and means effective when 5 one of said trunks becomes idle to cause said trunks to be tested.

2. In a telephone exchange system, a plurality of central offices for establishing telephone connections, a plurality of trunk lines 10 arranged in groups extending between said offices, an operator's position in one of said offices, a sender at said position arranged to send impulses to another of said offices to select thereat automatically a trunk line in 15 a particular group extending to a third of said offices, a signal at said position, automatic means in the second mentioned office for preventing the selection of said trunk line and for flashing said signal should all 20 trunk lines in the desired group be busy, and means effective when one of said trunks becomes idle to cause said trunks to be tested.

3. In a telephone exchange system, a plurality of central offices comprising a semi- 25 automatic, an automatic, and a manually operated office, a plurality of trunk lines arranged in groups extending between said offices, an operator's position in said semi-automatic office, a sender at said position arranged to send impulses over one of said trunk lines to said 30 automatic office, a signal at said position, a selector switch in said automatic office comprising trunk terminals arranged in groups, one of said groups being extended to said 35 manually operated office, automatic means associated with said selector switch for selecting a desired group of said terminals, for preventing further operation of said 40 automatic means and for flashing said signal should all trunk lines in the desired group be busy and for permitting further operation of said automatic means when a trunk line in the desired group is available to complete a trunk line connection to the said 45 manually operated office, and means effective when one of said trunks becomes available to cause said trunks to be tested.

4. In a telephone exchange system, a plurality of central offices comprising a semi-automatic, an automatic, and a manually 50 operated office, a plurality of trunk lines extending between said offices, an operator's position in said semi-automatic office, a sender at said position arranged to send impulses over one of said trunk lines to said 55 automatic office, a signal at said position, a selector switch in said automatic office comprising trunk terminals arranged in groups, one of said groups being extended to said 60 manually operated office, automatic means 65 associated with said selector switch for selecting a desired group of said terminals, for preventing further operation of said automatic means and for flashing said signal should all trunk lines in the desired group be busy and for permitting further operation of said automatic means when a trunk line in the desired group is available to complete a trunk line connection to the said 70 manually operated office, and means effective when one of said trunks becomes available to cause said trunks to be tested.

In witness whereof, I hereunto subscribe my name this 3rd day of November A. D., 1924.

ARTHUR B. SPERRY.
